UNITED STATES PATENT OFFICE

DON A. WEBER, OF FORT WAYNE, INDIANA, ASSIGNOR TO THE DEISTER CONCENTRATOR COMPANY, OF FORT WAYNE, INDIANA, A CORPORATION OF INDIANA

VIBRATING SCREEN

Application filed July 7, 1928. Serial No. 290,903.

The present invention relates to vibrating screens, particularly, for screening such materials as sand, gravel, and the like and has among its objects a motor operated screen 5 which may be constructed as a portable unit or set up as a permanent installation, depending upon the conditions which it is desired to meet.

Another object of the present invention is 10 a screen which may be so constructed that different kinds of screen fabric may be used without the necessity of readjustment of the operating parts.

A further object is a screen of the type or 15 kind indicated which shall have free moving parts and these parts well protected from dirt or other elements tending to interfere with efficiency in operation.

Still other objects will readily occur to those 20 skilled in the art upon reference to the following description and the accompanying drawings in which

Figure 1 is a perspective view of a portable screen unit embodying the present invention.

25 Figure 2 is a section on an enlarged scale, taken on line 2—2 of Figure 3.

Figure 3 is a vertical longitudinal section of the screen taken along the median line and showing the screen actuating unit.

30 Figure 4 is a more or less diagrammatic view similar to that of Figure 3 without the actuating unit.

Figure 5 is a view similar to that of Figure 4 but showing a different character of screen.

35 As indicated in the drawings, the screen unit consists of a frame 10 provided with spindles for wheels 11, and carrying a second frame 12 which forms the frame in which the meshed fabric 13 is stretched. The 40 latter may be any suitably meshed fabric of wire or other suitable material, wire being most commonly used.

The frame 12 is preferably arranged in 45 an inclined position and carries along its sides and upper end, inclined hopper plates 14, while the side hopper plates have at their lower edges deflecting plates 15 adapted to prevent the material being sifted from passing laterally from the edge of the meshed 50 fabric.

At its lower end, the frame 12 also carries a rectangular extension portion 16, within which may be suspended the tailings box 17, which latter may be provided with suitable handles 18 to facilitate its insertion 55 and removal.

The frame 12 may also have provided at its lower end the leg 19 which may or may not be adjustable and provides with the wheels 11 a three point base for the unit. 60 Frame 12, as mentioned above, carries stretched therein the meshed fabric 13, and this latter is secured at one end of the frame to fixed clamp members 20, by means of short bolts 21 with plates 22 to prevent tearing the fabric. At the other end of the frame, the screen fabric is secured by means of the U-clamps 25 to which the screen is secured, as by bolts 26, and one or several plates 27. 65

These U-clamps are drawn toward the end 70 12a of the frame 12 by means of bolts 28 and means are provided to permit the clamps 25 a swinging movement in a vertical plane by the knife edge bearing members 29 and 30, the former resting against the frame 12 and the latter being between the head 31 of bolts 28 and the back cross member of the clamp member 25, as shown clearly in Figures 3, 4 and 5. 75

Transversely arranged beneath the frame 12 is a channel member 40 carrying on its under side a casing 41 containing the screen actuating means which will be described more in detail later and this channel member is provided with suitable openings for the passage of the screen actuating rods 42 which are attached at their upper ends to a small channel 43 secured to a second channel 44, which in turn, is secured to the screen fabric 13. 80

The two channels 43 and 44 telescope and are secured together by the thumb nuts 45 located above the screen. 85

Within the casing 41, the screen actuating rods 42 are secured together by means of a yoke 53 connecting the rods preferably at their lower ends. These rods extend through the upper part of the casing to a sufficient distance beyond and are fixed to the channel member 43 in any suitable manner and, at 90 100

the point where they pass through the casing and the supporting channel member 40, felt washers 54 are provided to prevent passage of oil.

5 The rods 42 preferably fit in the openings in the upper part of the casing 41 so as to have a bearing therein and the lower ends of the rods are guided by means of a projection 55 on yoke 53 which extends into a 10 suitable hollow boss 56 and has bearing therein; the projection 55 being provided with a passage 57 therethrough so as to allow passage of oil into the boss. The effect of this 15 passage is not only to supply oil to lubricate the bearing in the boss 56 but as the yoke 53 vibrates, this passage forms a jet of oil which plays on the roller 60 so as to lubricate it and the cam 61.

20 On the upper side of yoke 53 is mounted 20 a roller 60 adapted to coact with a cam 61 fixed to the end of a shaft 62 extending from one side of the casing to a suitable motor 63, carried, preferably, at the upper end of the frame 12. The cam 61 is provided with one 25 or more teeth or projections 64 which act upon the roller 60 to cause the yoke and rods 42 to be pulled down and released with each revolution of the cam.

30 Mounted above the casing 41 and preferably upon the supporting member 40 is a comparatively strong compression spring 65 which abuts against the supporting member 40 at one end and at its upper end bears against a shoulder 66 of an adjusting nut 67 carried 35 upon a threaded stud 68 fixed in the channel member 43, as indicated clearly in Figure 2. This spring is compressed upon the downward stroke of the rods 42 and, when the cam has rotated further to release the yoke and rods, causes the upward movement of the channel 40 43 and therefore the screen 13 which is fixed thereto.

45 Figures 3, 4 and 5 indicate the proper adjustment of the screen fabric in the device. As indicated in these figures, the screen fabric 13 is clamped in the members 20 and 25 and drawn tightly longitudinally by means of the bolts 28 and the nuts thereon and is also drawn downwardly from a straight line position to a point somewhere below the latter, this being accomplished by providing the rods 42 of suitable length and drawing down the screen thereon by means of the thumb nuts 45. The amount of deflection below the 50 straight line position need be very small and with the parts arranged as shown, can be a fixed amount for all thicknesses of screen. The relation between the lower side of the screen in clamp 25, the lower side of the screen in clamp 20, and the upper side of the channel member 43 may be fixed and need not be changed. This is possible when placing the actuating mechanism under the screen 55 but is not readily accomplished in those mech-

anisms in which the actuating means is placed above the screen.

In changing from one thickness of screen to another, the difference in thickness will preferably be compensated for in the clamp 70 25 by the use of suitable shims 70, less shims, of course, being used with the thicker screen than with the thinner one. Figure 4 shows the use of three thin shims for example, while Figure 5 shows a single one. In lieu of shims, set screws may be placed in the upper arm of the clamp 25. 75

Now having described the invention and the preferred form of embodiment thereof, it is to be understood that the said invention is to be limited not to the specific details herein described and illustrated but only by the scope of the claims which follow. 80

I claim:—

1. A vibratory screen comprising a frame, 85 screen fabric therein secured under tension at opposite sides to said frame, means for drawing the central portion of said fabric to a position below the plane of its ends, and actuating means beneath said screen adapted to draw said central portion further from said plane and release it. 90

2. A vibratory screen comprising a frame, screen fabric therein secured under tension at opposite sides to said frame, and actuating means for said fabric adapted to maintain the intermediate portion of said screen below the plane of its ends and to cause said portion to move relatively to and in a path transverse to said plane, said path lying 100 wholly below said frame. 105

3. In a vibratory screen unit, a frame, a screen fabric supported at its ends therein, means for tensioning said fabric longitudinally of said frame, a substantially rigid member extending transversely across said fabric and secured to its underside, an actuating member secured to said first member and maintaining the latter below the plane of the ends of said fabric, a cam follower carried by said actuating member, a cam adapted to cause said follower and thereby said actuating member to move in a path transverse to said fabric and entirely below said plane, and means carried by said unit to 110 actuate said cam. 115

4. In a vibratory screen unit, a frame, a motor carried thereby, screen actuating means operated by said motor and mounted under said frame, a screen fabric mounted at its ends in said frame and adapted to be moved by said means in a direction transverse to its own plane, and means to fix the path of said movement below the plane of its ends. 120

5. In a vibratory screen unit, a frame, screen fabric, means at the ends of said frame for fixing said fabric therein, means secured to the underside of said fabric at an intermediate portion thereof and off-set from the 125 130

plane of the ends of said fabric, and means for maintaining the relative positions of said end fixing means and the other means when said fabric is in rest position adapted to 5 maintain their relative adjustment fixed irrespective of the thickness of the screen fabric.

6. In a vibratory screen unit, a frame, screen fabric therein, a channel member secured to the underside of said fabric, a longitudinally movable rod fixed perpendicularly to said channel, means to maintain said channel and that portion of the fabric to which it is attached displaced below the plane of 15 the ends of the fabric, means to move said rod and channel to cause further displacement and to release the same when said further displacement has been caused, and means to return said channel and rod to the position 20 of initial displacement.

DON A. WEBER.
